UNITED STATES PATENT OFFICE

1,935,366

CIGARETTE ROLLER

Jacob Ling, Little Rock, Ark.

Application April 27, 1932. Serial No. 607,741

2 Claims. (Cl. 131—5)

My invention relates to cigarette rollers or rolling devices and the main object is to provide a simple and efficient device by means of which cigarettes may be readily and quickly rolled, the device being of such nature and construction that it may be suitably encased and used at home or the office or adapted for carrying in the pocket or pocket book for use at any time.

Another object is to provide a device of this kind comprising a minimum of parts including a fabric apron or belt for rolling and packing the tobacco and a roller and guide and support means spaced apart to pass the ends of the apron and form a tobacco receiving bight therein whereby tobacco placed in said bight may be rolled and packed and finally covered or enclosed in the cigarette paper by simply pulling upon the apron in the proper manner.

With these and other objects in view the invention resides in the novel construction and arrangement of parts as hereinafter set forth and claimed, reference being had to the accompanying drawings of one preferred embodiment of the invention and a modification thereof and in which drawings

Figure 1 is a perspective view of the device as enclosed in a case for home or office use.

Figure 2 is a plan view, the case top being removed.

Figure 3 is an enlarged section along the line 3—3 in Figure 2.

Figure 4 is an enlarged cross section through the rollers showing the operation of the apron and the rolling of the cigarette paper around the tobacco.

Figure 5 is a plan view of the apron, a medial portion being broken away.

Figure 6 is a vertical cross section through a tobacco container as for use in the case shown in Figure 1.

Figure 7 is a section along the line 7—7 in Figure 6.

Figure 8 is a plan view of a modified form of the invention.

Figure 9 is an end view of the modification shown in Figure 8 as mounted in a pocket book, the latter being shown in section.

Figure 10 is a cross section through the modified form of the invention showing a portion of the pocket book and the mounting bar.

Figure 11 is a view similar to Figure 4 showing the method of forcing the paper downward preliminary to rolling it around the tobacco.

The first embodiment of my invention comprises a case including the bottom 1, slidably top

2, sides 3 and the front and rear ends 4 and 5. A laterally extending partition 6 is provided in the case adjacent or in the rear portion thereof. Secured between the front end 4 and this partition 6 and extended longitudinally in the case is a forming block 7 here shown as being made of wood and including a longitudinal groove 8 along one upper edge. It is understood however that a metal block of relatively less bulk may be employed if desired. A roller 9 is journaled at its ends 10 in the end 4 and partition 6 and extensions alongside and in parallelism with the upper edge of the block 7 above the groove 8 therein. A shaft or rod 11 is slidably passed through apertures 12 in the end 4 and partition 6 and extends alongside and parallels the roller 9 and a sleeve 13 is slidably and removably mounted on that portion of this shaft which lies between said end 4 and partition 6. The foregoing elements constitute the cigarette rolling apparatus proper and are used in connection with a forming band or strip 14 which comprises a rectangular ribbon of flexible fabric of a width slightly less than the length of the roller 9 and sleeve 13 and which is looped or folded around a wooden insert 15 at one end. The other end 16 of said band 14 is preferably though not necessarily scalloped as shown and the band itself is preferably of material similar to oil cloth having one rough side and one smooth side.

In the operation of rolling a cigarette the shaft 11 is drawn lengthwise almost entirely from the case and the sleeve 13 is removed. The band 14 is then laid over the forming block 7 with its rough side uppermost and a central portion is pressed downward over the roller 9 forming a bight designated throughout the drawings at 17 into which a quantity of tobacco T sufficient for a cigarette is placed. The shaft 11 is then pushed back into its normal position and the sleeve 13 is replaced leaving the bight 17 of the band 14 depended beneath the roller 9 and the sleeve and shaft assembly with the end portions of the band trained upwardly between the roller and sleeve as shown in Figure 3. The band is then worked back and forth longitudinally by grasping and pulling alternately upon each end causing the tobacco T in the bight 17 to be rolled and packed beneath the roller 9 and sleeve 13 as will be understood. With the band 14 in about the position shown in Figure 3 one edge of a cigarette paper 18 is inserted in the space between the end portions of the band as they pass downward between the roller and sleeve and these end portions are then drawn upward together and the

whole band and its enclosed tobacco and paper is pushed downward as shown in Figure 11. The cigarette paper 18 is thus forced downward between the roller and sleeve as shown and upon pulling outward and upward upon the end portion of the band carrying the wooden insert 15 and at the same time grasping and holding the other end portion and the exposed part of the cigarette paper the slack in the band will first be taken up and then the cigarette paper rolled around the tobacco as shown in Figure 4. When the band is pulled completely out from between the roller 9 and sleeve 13 the rolled cigarette will drop to the bottom 2 of the case from which it may be removed by tipping said case and allowing the cigarette to roll out through the slot 19 in the side 3. It is understood of course that the paper 18 has its margin 20 coated with a suitable adhesive which may be provided with the paper or applied as needed from a can 21 carried in the chamber 22 of the case between the partition 6 and rear end 5. It will be apparent that this arrangement provides a simple and convenient means for rolling cigarettes and that they may be loosely or tightly packed as desired by varying the tension on the band 14 as it is manipulated in the preliminary rolling and packing of the tobacco as set forth. If desired the use of the sleeve 13 may be dispensed with and the shaft 11 itself be made larger and arranged to rotate freely as the band is manipulated. The rough side of the band 14 has a tendency to grip and carry the cigarette paper along as it is rolled while the smooth side facilitates the easy movement of the band over the roller and sleeve as will be understood.

Figures 6 and 7 show a tobacco container and dispenser for use with the cigarette rolling device as described and this container comprises a can 23 in general form similar to the usual tobacco tin but having a lid 24 at its lower end. The upper end or top 25 has a longitudinal slot 26 and a tube 27 is journaled horizontally through the can beneath this slot 26 and through apertures 28 in the sides 29. The tube 27 has a longitudinal slot 30 through its wall adapted to register with the slot 26 when the tube is turned to bring this slot 30 upward as will be understood, the tube being rotated readily by grasping its extended ends 31 with the fingers. With the slot 30 disposed downwardly as shown in the drawings the can 23 is inverted and tobacco therein will fall into the tube. The tube 27 is then rotated to bring the slot 30 into registry with the slot 26 and the tobacco in the tube will fall downward through the slots and may fall into the bight 17 formed in the band 14 as set forth hereinbefore. The size of the tube 27 is such that the tobacco therein is the right quantity for a cigarette thus making it possible to readily measure off the desired amount of tobacco each time a cigarette is rolled. When not in use the can 23 sits in the case alongside the side 3 and the extended ends 31 of the tube 27 rests in slots 32 and in the end 4 and partition 6 as shown in Figure 2.

Figures 8, 9 and 10 illustrate a modified form of the invention suitable for mounting in a pocket book or hand bag A and on the inner face of one of the sides B thereof, a supporting strip 33 being mounted across the vertical legs C of the usual U-shaped frame D on which strip the invention is secured. In this embodiment the forming block 34 is formed of wood secured to the strip 33 by

screws 35 and having a groove 36 near its outer margin and terminating in a rounded nose portion 36 above or outwardly of said groove. One leaf or strap 38 of a hinge 39 is secured by screws 40 to one end of the block 34 and a shaft 41 is secured at one end in the free leaf 42 of said hinge whereby the shaft may rest alongside the nose portion 37 of the block or may be swung outwardly away from the block as indicated by the arrow in Figure 8. A sleeve 43 is mounted loosely on the shaft 41 and the cigarette is rolled in the manner set forth hereinafter by manipulating the band 14 between this sleeve 43 and the rounded nose portion 37 of the block. This nose portion 37 takes the place of the roller 9 but it is obvious that a roller may be employed if desired. The shaft 41 and sleeve 43 are releasably held in proper position alongside the nose portion of the block 34 by a stop plate 44 secured by screws 45 to the end of the block and a latch 46 pivotally mounted at 47 on the stop plate, the former having its outer end 48 notched as shown to receive the end of the shaft 41 while the latter has a recess or notch 49 adapted to slip over and partially encircle the said shaft. The arrangement is such that the shaft may be released to swing away from the block 34 on the hinge 39 by simply swinging the latch 46 downward as will be understood. The shaft and sleeve are of course swung away from the block when the bight is formed in the band 14 and is being filled with the tobacco.

It is thought that further details of the operation and advantages of the invention will be understood without further description at this point.

While I have herein set forth certain preferred embodiments of my invention it is understood that I may vary from the same in minor structural details so as best to construct a practical device for the purposes intended, not departing from the spirit of the invention and within the scope of the appended claims.

I claim:

1. In a cigarette roller, an elongated forming block having a groove in one side and having a rounded nose portion above this groove, a shaft hinged to one end of the forming block and adapted to normally lie alongside the nose portion thereof, a sleeve journaled on the shaft, a stop plate secured to the other end of the forming block and having a notch in its end to receive the free end of the shaft in its normal position, and a latch pivoted on the stop plate and adapted to hold the shaft in engagement with the notch in the said plate and a fabric band adapted to be trained over and between said sleeve and the nose portion of the block.

2. In a cigarette roller, an elongated forming block having a groove in one side and a rounded nose portion above the said groove, a hinge including two pivotally connected leaves, one leaf of the hinge being secured to one end of the forming block, a shaft secured at one end to the free leaf of the hinge and adapted to normally rest alongside and parallel with the nose portion of the forming block, a sleeve journaled on the shaft, a stop plate secured to the other end of the forming block and having a notch in its end to receive the free end of the shaft in the normal position thereof, and a latch pivoted at one end to the stop plate and having a notch for locking engagement with the end of the shaft.

JACOB LING.
